US00D767075S

(12) **United States Design Patent** (10) **Patent No.:** **US D767,075 S**
Grossman et al. (45) **Date of Patent:** **** Sep. 20, 2016**

- (54) **ERGONOMIC GRIP FOR A SLIDE OF SEMIAUTOMATIC FIREARM**
- (71) Applicants: **David A. Grossman**, Mascoutah, IL (US); **Jonathon D. Grossman**, Mascoutah, IL (US); **Bruce K. Siddle**, Millstadt, IL (US)
- (72) Inventors: **David A. Grossman**, Mascoutah, IL (US); **Jonathon D. Grossman**, Mascoutah, IL (US); **Bruce K. Siddle**, Millstadt, IL (US)
- (**) Term: **14 Years**
- (21) Appl. No.: **29/517,980**
- (22) Filed: **Feb. 19, 2015**
- (51) LOC (10) Cl. **22-01**
- (52) U.S. Cl. **USPC D22/108**
- (58) **Field of Classification Search**
 USPC D22/103, 108; D21/572-575; D8/68
 CPC F41C 23/10; F41C 23/14; F41C 23/16;

(57) CLAIM

The ornamental design for an ergonomic grip for a slide for a semiautomatic firearm, as shown and described.

DESCRIPTION

FIG. 1 is a perspective view of an ergonomic grip for a slide for a semiautomatic firearm showing our new design;
 FIG. 2 is an alternate perspective view of the grip of the firearm of FIG. 1;
 FIG. 3 is an alternate perspective view of the grip of the firearm of FIG. 1;
 FIG. 4 is an alternate perspective view of the grip of the firearm of FIG. 1;
 FIG. 5 is a side elevational view of the grip of the firearm of FIG. 1;

FIG. 6 is a side elevational view of the grip of the firearm FIG. 1;
 FIG. 7 is a partial enlarged front view of the grip of the firearm of FIG. 1;
 FIG. 8 is a partial enlarged rear view of the grip of the firearm of FIG. 1;
 FIG. 9 is a top view of the grip of the firearm of FIG. 1;
 FIG. 10 is a bottom view of the grip of the firearm of FIG. 1;
 FIG. 11 is a perspective view of alternate embodiment of an ergonomic grip for a slide for a semiautomatic firearm showing our new design;
 FIG. 12 is an alternate perspective view of the grip of the firearm of FIG. 11;
 FIG. 13 is an alternate perspective view of the grip of the firearm of FIG. 11;
 FIG. 14 is an alternate perspective view of the grip of the firearm of FIG. 11;
 FIG. 15 is a side elevational view of the grip of the firearm of FIG. 11;
 FIG. 16 is a side elevational view of the grip of the firearm FIG. 11;
 FIG. 17 is a partial enlarged front view of the grip of the firearm of FIG. 11;
 FIG. 18 is a partial enlarged rear view of the grip of the firearm of FIG. 11;
 FIG. 19 is a top view of the grip of the firearm of FIG. 11;
 FIG. 20 is a bottom view of the grip of the firearm of FIG. 11;
 FIG. 21 is a perspective view of alternate embodiment of an ergonomic grip for a slide for a semiautomatic firearm showing our new design;
 FIG. 22 is an alternate perspective view of the grip of the firearm of FIG. 21;
 FIG. 23 is an alternate perspective view of the grip of the firearm of FIG. 21;
 FIG. 24 is an alternate perspective view of the grip of the firearm of FIG. 21;
 FIG. 25 is a side elevational view of the grip of the firearm of FIG. 21;
 FIG. 26 is a side elevational view of the grip of the firearm FIG. 21;
 FIG. 27 is a partial enlarged front view of the grip of the firearm of FIG. 21;
 FIG. 28 is a partial enlarged rear view of the grip of the firearm of FIG. 21;
 FIG. 29 is a top view of the grip of the firearm of FIG. 21; and,
 FIG. 30 is a bottom view of the grip of the firearm of FIG. 21.

The broken lines shown in the drawings are for illustrative purposes only and form no part of the claimed design.
